UNITED STATES PATENT OFFICE.

NEIL McLEAN, OF WATSONVILLE, CALIFORNIA.

GRAIN-SAVING ATTACHMENT FOR SEPARATORS.

SPECIFICATION forming part of Letters Patent No. 253,936, dated February 21, 1882.

Application filed August 31, 1881. (No model.)

To all whom it may concern:

Be it known that I, NEIL McLEAN, of Watsonville, county of Santa Cruz, State of California, have invented a Grain-Saving Attachment for Separators; and I do hereby declare the following to be a full, clear, and exact description thereof, reference being had to the accompanying drawings, making part of this specification, in which—

10 Figure 1 is a perspective view of my grain-saving attachment. Fig. 2 is a side elevation of the same, showing its position in relation to the straw-carrier frame. Figs. 3 and 4 are details to be referred to.

15 My invention relates to grain-saving devices for thrashing-machines; and it consists in the details of construction of a supplemental attachment to the straw-carrier, whereby the straw is stirred and agitated as it leaves the 20 carrier, so the grain mechanically entangled in the straw may escape and be recovered, all of which is hereinafter described and specifically claimed.

25 In order that those skilled in the art may make and use my invention, I will proceed to describe the manner in which I have carried it out.

In the said drawings, C C are the side boards of the saving attachment, and A' is a fixed inclined bottom, the lower edge, a', of which slightly overlaps a perforated screen, K, the pitch of which is controlled by a slotted supporting-bar, L, and set-screw.

35 Beneath the screen K is a solid inclined floor, A'', at the lower end of which is a gutter and 40 conveyor, I, and attached spout J, for conducting off the grain, as hereinafter set forth.

Journalized in the side C, over screen K, is a shaft, M, provided with radial fingers a a, and 45 journalized over floor A' are two shafts, B B', each provided with a set of radial fingers, t t, and reels A A.

The shafts M, B, and B' are provided with pulleys and belts driven from the main pulley, 50 whereby they are revolved in the direction in-

dicated by the arrows, and with them are revolved the fingers and reels.

On the end of shaft M is a crank, P, which oscillates, through the medium of pitman Q, a rock-shaft, R, which passes beneath the attachment, and has a projection passing up through floor A'' at e, and, striking the sieve K at each turn of shaft M, gives it a rising-and-falling motion, by which the grain is shaken through the perforations onto floor A'', whence 55 it falls into the trough, and is conveyed by the screw-conveyer I to a spout, J, to be conducted to the cleaning-shoe.

The attachment is placed against the end of the straw-carrier frame S, as seen in Fig. 2, 60 and as the straw passes from the carrier it passes between the sides C, over shafts B B' with their revolving fingers and reels, which loosen and agitate the straw, so that the entangled grain may fall upon floor A', whence 65 it slides upon screen K and passes through the perforations. Short straw and chaff also fall on floor A' and pass upon screen K, and, if allowed to accumulate, would interrupt the passage of the grain. The short straw and chaff 70 are thrown by the fingers a a out of the attachment beneath the straw-carrier in a direction opposite to the feed of the straw.

Having thus described my invention, what I claim as new, and desire to secure by Letters 75 Patent, is—

The supplemental attachment to the straw-carrier of a grain-separator, consisting of the spout formed by side boards, C C, having the inclined floor A', and revolving shafts B B', provided with fingers t t, and reels A A, the screw-conveyer I, spout J, perforated screen K, and revolving shaft M, provided with fingers a a, all constructed, arranged, and operated as set forth.

85 In witness whereof I have hereunto set my hand.

Witnesses: NEIL McLEAN.

GEO. H. STRONG,
FRANK A. BROOKS.
